ROBERT E. CAMPBELL, OF BERKELEY, CALIFORNIA.

ROTARY VALVE.

1,295,429.

Specification of Letters Patent. Patented Feb. 25, 1919.

Application filed May 16, 1917. Serial No. 168,975.

To all whom it may concern:

Be it known that I, ROBERT E. CAMPBELL, a citizen of the United States, residing at Berkeley, in the county of Alameda and State of California, have invented new and useful Improvements in Rotary Valves, of which the following is a specification.

This invention relates to a rotary valve particularly adapted for use in connection with internal combustion engines of the four-cycle type.

One of the objects of the present invention is to provide a simple, easily applied rotary valve for internal combustion engines, which is self-seating in operation and provided with a plurality of ports alternately operable as exhaust and intake ports to permit uniform expansion and low temperature during operation. Another object of the invention is to so arrange the ports that a plurality of the ports is opened both during the exhaust and intake stroke, thereby permitting a free admission and discharge of the gases and also a slow rotation of the valve as compared with crank shaft speed. For instance, by providing six ports in the valve it becomes possible to rotate the valve at a ratio of one revolution to twelve of the engine shaft, thereby reducing wear and leakage through the valve to a minimum. Further objects will hereinafter appear.

The invention consists of the parts and the construction and combination of parts as hereinafter more fully described and claimed, having reference to the accompanying drawings, in which—

Figure 1 is a vertical, central section through the valve, taken on line 1—1 of Fig. 2.

Fig. 2 is a plan cross section on line 2—2 of Fig. 1.

Fig. 3 is a similar section on line 3—3 of Fig. 1.

Fig. 4 is a diagrammatic view showing the valve movement.

Referring to the drawings in detail, A indicates the cylinder of an internal combustion engine, 2 the piston and B a valve head which may be formed integral with the cylinder or secured to same. The valve head is provided with a frusto-conical, annular channel 4 for the reception of a valve 5 of similar shape, which, in this instance, is driven by a set of worm gears 6 and 7 at a rate of one to twelve of the engine shaft;

the connection between the gear 6 and the valve 5 being formed by a hub-like extension 8 and a spline 9 which permits vertical movement of the valve with relation to the gear, as will hereinafter be described. The hub 8 being secured to the valve proper by means of a plurality of spoke-shaped arms 10 permits lubrication of the inner and outer surface 11 of the valve. The annular channel 4, formed in the valve head B, divides the valve head into two separate portions, to-wit, an inner central member or head 12, in which is formed a central chamber 13 which communicates with the cylinder, and a plurality of radially disposed ports 14. There are six ports in the present instance indicated by the numerals 8^a and 8^b, and these ports are in turn divided into two sets, the set 8^a serving as intake ports and the set 8^b serving as exhaust ports. Each set of ports is offset with relation to each other, that is, the three exhaust ports are evenly spaced with relation to each other and the three intake ports are evenly spaced with relation to each other, but the three exhaust ports are positioned circumferentially closer to one of the intake ports, as will herein-after be described.

The second portion of the valve head consists of an exterior annular wall 15, in one side of which is formed three inlet ports indicated by the numeral 1^a communicating with an intake chamber 16, and in the opposite side of which are formed three exhaust ports, indicated by the numerals 1^b, communicating with an exhaust chamber 17. The inlet ports 1^a are in alignment with the intake ports 8^a, formed in the central head member, and the exhaust ports 1^b are in alignment with the exhaust ports 8^b. The exhaust chamber is otherwise water-jacketed, as at 18, to permit cooling of the valve and the exterior wall 15.

Formed in the valve proper are six ports 19. These ports are radially positioned and are, furthermore, evenly spaced to permit alternate registration with the inlet and exhaust ports formed in the inner and outer sections of the valve head. This alternate registration takes place during the rotation of the valve which is driven through the gears 6 and 7 and is best explained by referring to the diagrammatic view shown in Fig. 4. In this view the numeral 15 represents the outer wall of the valve head, in which is formed the intake ports 1^a and the

exhaust ports 1^b and 5 represents the valve in which are formed the ports 19. The circles representing the outer wall section of the valve head and the valve are here graduated into forty-eight subdivisions; the spacing between the intake ports in the wall 15 being divided into eight sections and the spacing between the exhaust ports being also divided into eight sections. The exhaust ports are, however, positioned circumferentially three spaces closer to the first intake port, indicated at 20, thereby bringing the first intake port 20 and the first exhaust port 21 three subdivisions closer and similarly increasing the space between the last intake port 22 and the last exhaust port 23 by three spaces. In other words, there are nine subdivisions between the ports 22 and 23 and only five subdivisions between the ports 20 and 21.

This circumferential changing or shifting of the exhaust ports with relation to the intake ports makes it possible to evenly space the ports in the valve and also makes it possible to bring the ports in the valve into alternate register with the inlet ports and the exhaust ports and, furthermore, makes it possible to open both sets of ports at one time. In view of the fact that these ports are provided, it also makes it possible to impart a slow rotary movement to the valve during the operation of the engine; that is, one revolution of the valve permits twelve revolutions of the engine crank shaft or six complete cycles or operation where a four-cycle type of internal combustion engine is employed.

Commencing with the piston in its upper position, the port 8 in the valve will assume the position with relation to port 20 shown in Fig. 4, that is, when the piston is in position to move in a downward direction on the suction stroke. The one to twelve speed ratio between the crank shaft and the valve causes the port 8 to move from the position shown into register with the sub-division indicated at 2^a, while the piston travels downwardly through the cylinder to charge the latter. The movement of the port from the position shown to the subdivision 2^a causes registration with port 20 and, therefore, permits a charge to be drawn through the ports while in registration. The valve travels from the subdivision 2^a to the subdivision 4^a, during the compression stroke of the piston, and travels from the subdivision 4^a to the subdivision 6^a during the firing stroke. The port in the valve will then be directly opposite the exhaust port 21 and will move across said port during the exhaust stroke of the piston, thereby permitting a complete scavenging of the cylinder and finally assumes the position shown at 8^a on the diagrammatic view of the valve after the four cycles have been completed. In other

words, 1/6 of a revolution is imparted to the valve during the four cycles of operation or during two revolutions of the crank shaft.

Three ports in the valve will register simultaneously with the three intake ports in the outer and inner sections of the valve head and three ports will also register with the aligned exhaust ports formed in the outer and inner sections of the valve. A comparatively large valve opening is in this manner obtained and a free passage for incoming and exhausting gas is, therefore, permitted, thereby causing a more complete charging and scavenging of the cylinder during the four cycles of operation.

Another result obtained will be as follows: Each port formed in the valve serves first three times as an intake port and then three times as an exhaust port. This is of considerable importance as it permits a uniform heating or cooling of the valve, thereby maintaining an even expansion and even wear when operating. The valve is, furthermore, tapered both exteriorly and interiorly and as this taper is of the standard "Morse" angle and the speed of revolution is so extremely low it can readily be seen that whatever wear takes place is automatically taken up, as the spline on the hub 8 permits the valve to settle as wear takes place.

For the purpose of constantly lubricating the valve during its rotation and also the driving gears 6 and 7, a cap 27 has been provided. This cap may be filled with oil and, therefore, forms a well on top of the valve from which the oil can continuously drain down between the wearing surfaces. The valve and gears are in this manner automatically lubricated and as they are constantly flooded with oil it can readily be seen that an ideal condition, as far as lubrication is concerned, is established.

The inner portion of the valve head 13 is preferably water-jacketed, as shown at 28, and forced circulation may be maintained through said jacket space by extending a tube 29 through the hub 8 of the valve. Water entering through this tube passes through the jacket space formed in the head 13 and may then enter the cylinder jacket 30, as shown. The jacket space 18 may also communicate with the cylinder jacket and any suitable means for maintaining a circulation therethrough may be provided. The valve proper can in this manner be maintained comparatively cool, first, by the water circulation maintained both interiorly and exteriorly thereof, and, second, by the alternate use of the ports for inlet and exhaust purposes.

While six sets of ports are here shown, I wish it understood that the number may be increased, for instance to eight or more, thereby further decreasing the speed of revolution. The one objection to employing

more ports than shown is the necessary increase in exterior diameter. This, however, is permissible where an engine of large size is employed.

5 I also wish it understood that the materials and finish of the several parts of the rotary valve may be such as the experience and judgment of the manufacturer may dictate.

10 Having thus described my invention, what I claim and desire to secure by Letters Patent is—

15 1. A rotary valve comprising a head member divided by a tapering annular channel into an outer and an inner casing section which sections are formed with aligned inlet and exhaust ports establishing communication with a central chamber provided in the inner section, said head member being water jacketed, a water inlet tube extending upwardly from the inner section, a rotary valve arranged in the annular channel of the head member for controlling the inlet and exhaust ports, a hub part rotatably supported 20 on the tube and connected to the valve by a plurality of arms whereby a lubricant may flow to both the inner and outer faces of the valve, a gear splined to the hub for relative sliding, and a cover plate inclosing the upper end of the valve, gear and hub part and forming a lubricant chamber.

25 2. A rotary valve comprising a head member divided by a tapering annular channel into an outer and an inner casing section which sections are formed with aligned inlet

and exhaust ports establishing communication with a central chamber provided in the inner section, a water inlet tube extending upwardly from the inner section, a rotary valve arranged in the annular channel of the head member for controlling the inlet and exhaust ports, a hub part rotatably supported on the tube and connected to the valve, and a gear splined to the hub part for sliding whereby the valve may automatically maintain a proper seating in the channel as wear occurs.

30 3. A rotary valve comprising a substantially cylindrical head member provided with a set of ports on each side of a diametrical line therethrough, a substantially Y-shaped manifold for each set communicating with all the ports thereof and conforming to the exterior of the head member, the latter being divided concentrically by an annular channel into an outer and an inner casing section, a cylindrical valve rotatable in the channel to control the sets of ports, said valve extending above the inner casing section, a water jacket capping the latter and arranged within the upper end of the valve, a water supply pipe extending upwardly from the jacket, valve driving means journaled on the pipe and connected to the valve by radiating spokes overlying the water jacket, and a housing for the valve driving means.

35 In testimony whereof I have hereunto set my hand.

ROBERT E. CAMPBELL.
